UNITED STATES PATENT OFFICE.

JOHN CARRIGAN, OF SEATTLE, WASHINGTON.

THERMAL CIRCUIT-CLOSURE.

1,136,407.

Specification of Letters Patent. Patented Apr. 20, 1915.

Application filed July 3, 1913. Serial No. 777,286.

To all whom it may concern:

Be it known that I, JOHN CARRIGAN, a citizen of the United States, residing at Seattle, in the county of King and State of Washington, have invented certain new and useful Improvements in Thermal Circuit-Closures; and I do hereby declare the following to be a full, clear, and exact description of the invention, such as will enable others skilled in the art to which it appertains to make and use the same.

This invention relates to fire alarm systems, and specially to a combined thermally and electrically controlled system.

15 The object of the invention is to provide a thermostat having electrical connections with a suitable alarm device whereby the latter will be actuated when the temperature within the room wherein the thermostat is located rises above or falls below predetermined degrees.

20 A further object is to provide an alarm system having suitable electrical devices whereby the system may be tested from time to time to determine the operability thereof.

25 In the accompanying drawing, Figure 1 represents a front elevation of the thermostat showing the same connected with the alarm circuit. Fig. 2 represents a vertical 30 sectional view through the thermostat. Fig. 3 represents a vertical sectional view therethrough taken at right angles to Fig. 2. Fig. 4 represents a horizontal sectional view through the thermostat, and, Fig. 5 represents a detail view of the thermostat housing and cover therefor.

35 Referring to the drawings in detail, the numeral 1 indicates the base of the housing which is adapted to be secured to the 40 wall of a room to be equipped with the alarm system. A porcelain plate 2 is fixed in the front end of the base 1 and carries an annular ring 3 which projects outwardly of the plate 2 and is provided with a removable cover 4 having a glass front 5. The removable cover 4 is provided with bayonet slots 6 which are adapted for locking engagement with lugs 7 carried by the ring 3. The plate 2 is provided with graduated markings 8 representing a preferred thermometric scale. An indicating hand 9 is pivoted on a shaft 10 mounted through the plate 2, and fixed on the opposite side of said plate to a thermostatic coil 11. The 50 opposite extremity of the coil 11 is fixed to a post 12 and the extreme free end of

the shaft 10 is mounted through a bracket 13 fixed to the rear side of the plate 2 by the screws 14. A guard plate 15 is also secured to the rear side of the plate 2 for 60 protecting the coil 11.

The under side of the ring 3 is slotted at 16 and the lower portion of the plate 2 is slotted at 17 to permit the atmospheric air to penetrate the casing for the thermostat 65 and to reach the coil 11 to act thereon and actuate the indicator hand 9 to register the temperature within the room.

70 It will be understood that the plate 2 is formed of porcelain or other suitable insulating material in which is formed an arcuate slot 18, located directly below the markings 8 and receiving a pair of adjustable contact posts 19 and 19^a. The posts 19 and 19^a carry conductors 20 and 20^a, respectively, 75 which extend through an insulating sleeve 21 secured in the wall of the base 1. A second contact element 22 is suitably fixed to the shaft 10 and carries a conductor 23 positioned through an insulating sleeve 24 also 80 fixed in the side of the base 1.

85 The conductors 20 and 20^a are joined within the sleeve 21 which extends from the thermostat and is connected at its opposite extremity to two sets of batteries A and B. The other conductor 23 of the thermostat is connected with an electrical alarm bell C, an annunciator D and lamp E by suitable branch conductors F. The electrical devices C, D and E are also connected by the conductor G and branch conductors H to the opposite pole of the batteries A and B.

90 The circuit thus described including the alarm bell, annunciator and lamp is normally broken at the thermostat when the hand 9 thereof is located between the contact posts 19 and 19^a and is closed at such time when the heat or cold in the compartment in which the thermostat is located increases or decreases to such a degree as to cause the indicator hand 9 to move under the influence of the coil 11 and contact with either of the contact posts 19 and 19^a. Thus the circuit is closed through the batteries 100 A and B, conductor 20, either contact post 19 or 19^a, hand 9, conductor 23, the several branch conductors F, the electrical devices C, D and E, and returning to the batteries A and B through the conductor G and 105 branch conductors H.

110 A suitable push button I, or other circuit

closing device is connected with the conductors 20 and 23 intermediate the thermostat and the electrical devices C, D and E for testing the condition of the batteries

5 A and B.

What I claim is:—

A thermostat comprising a housing having an outturned flanged edge, an insulating plate having a central aperture and an arcuate slot therein attached to said flanged edge, a thermostat coil mounted in said housing, a shaft connected to said coil to be actuated thereby and running through said central aperture, a needle attached to said shaft 10 and actuated thereby, and a plurality of contact posts adjustably mounted in said arcuate slot and adapted to be contacted with by said needle to close an alarm circuit, said contact posts consisting of a shaft

portion having a head portion at one end 20 and a threaded portion at the opposite end, adapted to adjustably play through said arcuate slot, a washer mounted on said shaft between said head portion and said insulating plate adapted to bind a circuit wire 25 between said head portion and said washer and to rest against said plate, and a sleeve-like nut threaded upon the opposite portion of the shaft and adapted to bind said contact post in adjusted position and to receive the contact of said needle.

In testimony whereof I have signed my name to this specification in the presence of two subscribing witnesses.

JOHN CARRIGAN.
